UNITED STATES PATENT OFFICE.

BENJAMIN HOLBROOK, OF CHICAGO, ILLINOIS, ASSIGNOR TO THE HOLBROOK & MANN SANITARY EXHAUST VENTILATING COMPANY.

VENTILATOR.

SPECIFICATION forming part of Letters Patent No. 392,559, dated November 6, 1888.

Application filed August 19, 1887. Serial No. 247,334. (No model.)

To all whom it may concern:

Be it known that I, BENJAMIN HOLBROOK, of Chicago, in the county of Cook and State of Illinois, have invented certain new and useful 5 Improvements in Ventilators, of which the following is a full, clear, and exact description, reference being had to the accompanying drawings, in which—

Figure 1 is a front elevation. Fig. 2 is a 10 vertical section, and Fig. 3 is a vertical section at right angles to that shown in Fig. 2.

This invention relates to that class of ventilators in which the consumption of oxygen by combustion is relied on to create a draft of air 15 and the ascending heated currents are relied on to carry off the unconsumed air and gas. As heretofore constructed, a gas-jet or other flame has been arranged in an open tube or flue, through the lower end of which the air 20 rises freely to and around the flame, and through the upper end of which the heated and expanded remnant of unconsumed air and gas passes away and is discharged. The action 25 of the apparatus as thus constituted is destitute of energy, slow, and of little value for the purposes of ventilation.

The object of my invention is to increase the energy and efficiency of this class of ventilators, so as to render them capable of exhausting 30 large quantities of air in a comparatively short time.

In this class of ventilators, for purposes of convenience of description, the current which rises to the flame from the apartment to be 35 ventilated may be termed the "supply-current" and the current of unconsumed air and gas that rises from the flame may be termed the "discharge-current."

The principle of my invention consists in 40 introducing into the apparatus a mode of operation similar to that of the common blow-pipe—that is to say, in reducing the supply-passage into a contracted orifice or orifices and delivering the supply-current through 45 said orifice or orifices directly into or against the flame, which causes immediately great energy of combustion, the liberation of considerable heat, and the establishment of an active current through the supply-passage from the 50 compartment to be ventilated. One of the

best forms in which I have applied this principle and demonstrated its great value in increasing the energy and efficiency of the ventilation is represented in the drawings, in which—

A indicates an ordinary burner of any suitable description; B, the passage by which the discharge-current escapes; C, the passage through which the supply-current ascends from the room to be ventilated, and d the orifice through which the air blows from the supply-passage directly into and against the gas-flame.

In the form which I have here shown the supply-passage extends in the form of a siphon 65 from a point below the level of the burner up above the gas-flame, and then down alongside of or around the discharge-passage to a point opposite to the burner, so that the supply-current when once started in motion is siphoned, 70 as it were, to the burner, and is heated more or less while on its way. This heating of the supply-current is an improvement, but is not indispensable, the main principle of my invention being entirely independent of such preliminary heating.

Except by way of improvement, the form of the supply-passage is immaterial to the operation of my new principle of ventilation, and even the passage itself may be omitted and 80 the jets of air introduced directly from the apartment to be ventilated by means of the small jet holes or slit d, arranged to enable the air to blow immediately and directly into and against the flame within the flue, the lower 85 end of which is closed.

In my improvement it will be observed that the discharge-passage is always separated from the supply-passage or source of air by means of a partition or wall, in passing which the 90 air is divided or reduced into a jet or jets, and thus projected in a stream or streams directly into or against the flame.

The burner is situated in a tube or chamber closed at its lower end, provided with a sufficiently wide flue above for the escape of waste products and residue of combustion, and with a lateral jet or orifice, through which the supply air is concentrated into a small or thin stream or streams and forced directly against 100

the flame of the burner, the whole being arranged so that the burning tends to produce a partial vacuum in the lower end of the tube or chamber, while the heated column, escaping through the flue, prevents the air from entering downward through said flue to supply the flame with oxygen, and thus a strong draft is induced through the lateral jets or orifices, which impinges with great force directly 5 against the flame and produces the effect of a blow - pipe thereon. The deflection of the flame laterally by the blow-pipe action causes it to heat the wall of the tube or chamber, and thus may incidentally increase the upward 10 draft through the escape-flue and the inward rush of air through the lateral jets or orifices. 15

I claim as my invention—

1. The combination of a ventilating - flue provided with a contracted inlet-orifice and 20 a burner arranged therein so that the orifice delivers the supply-current in a stream directly into and against the flame, substantially as described.

2. The combination of a ventilating - flue provided with a contracted inlet - orifice, a 25 burner arranged therein, as described, and a supply flue or passage arranged so as to confine the supply-currents around or in contact with the wall of the discharge-flue, whereby the supply-current of air will be heated previous to its delivery into the flame, substantially as described.

3. The combination of a tube or chamber closed at its lower end and terminating in an escape - flue at its upper end, and a burner 30 within it, said tube being provided with a contracted inlet-orifice, which directs the incoming air into and against the flame of the burner, creating a blow-pipe-like action, substantially as described.

BENJAMIN HOLBROOK.
